SALAD BOWL

Efrem M. Ostrowsky, Highland Park, Ill., assignor to Jules P. Gits and Joseph A. Gits, both of River
Forest, Ill.

Application October 10, 1957, Serial No. 48,046

Term of patent 14 years

(Cl. D44—15)

FIG. 2

FIG. 3

Fig. 1 is a plan view of a salad bowl embodying my design;

Fig. 2 is a side elevational view of the salad bowl of Fig. 1; and

Fig. 3 is a bottom view of the salad bowl of Figs. 1 and 2.

I claim:

The ornamental design for a salad bowl, as shown.
